Design No. 326 - James L. Jackson Design for Grace frame and slender
Patented October 15, 1958

FIG. I

FIG. II

FIG. III

J. L. JACKSON

Des. 326

James S. Jackson of New York N. Y.
Letters Patent. No. 326. Dated Oct. 15. 1850

The Schedule referred to in these Letters Patent and making part of the same.

To all whom it may concern:

Be it known that I, James S. Jackson of the City, County, and State of New York, have produced a new Ornamental design for a grate frame Summerpiece and fender and I do hereby declare the following to be a full, clear and exact Description of the same, reference being had to the annexed Drawings, making as part of this Specification, in which

Fig. 1 is a view of the frame and summer piece.

Fig. 2 is a section or plan of the same.

Fig. 3 is a front view of the fender.

Fig. 4 is a top view of the same.

Fig. 5 is a section of the fender showing the arrangement of the floor pieces.

My design is produced as follows. The outer edge of the grate frame has a projecting moulding consisting of a convex and concave bead combined & is shown at (a, a) forming a band for the sides. Immediately within this there is in bold relief a fluted semicircular arch (b, b) banded spirally as seen at (c, c). At the keystone of this I affix an ornament consisting of right & left scrolls of leaves and shell-work as seen at (d). From this arch there next follows a deeply recessed space formed by a concave (e, e) terminating in a

narrow moulding (f.f.) which finishes the grate frame, and forms the open arch for the fire place. The summer piece is a flat plate shaped to fill the space within the moulding (f.f.) as usual. It is ornamented at (g) by an arch, fluted & banded in a manner similar to the first arch (b.c.) but of less dimensions, and having also an ornamented keystone as at (i). A recessed space follows, ornamented in the top by circular mouldings resting upon brackets of scroll work as shown at (h.l.). A panel is formed in the lower part of this space by a cross-moulding (m) which is filled with leaves & scrolls as shown at (n). (o) is a concave forming a recess like that at (e). The centre space is finished with two panels of fret work (p.p) covered by a semi-circular panel filled with radial tracery (r).

The fender (Figs. 3, 4, 5) consists of a semi-circular fence having a projecting plinth (s), the lower part of which is a richly scalloped moulding terminating at the sides and in front in a scroll (t.t.t.) forming feet. Above the plinth is an ogee band pierced through with numerous apertures, the spaces intervening being filled with scrolls and mouldings as shown at (u). The top edge has a round moulding (v) on the ends of which are two knobs (w.w).

The floor of the fender consists of a plate (x) Figs. 4 & 5 resting upon projections as shown in the section Fig. 5. It is ornamented on the upper side by radial panels as shown and has a piece or plate of metal (y) let into it ornamented with a circular piece of scroll work and with diaper work as shown clearly in the drawings.

What I claim as my production herein and desire to secure by Letters Patent is the combination and general arrangement of the figures and ornaments as set forth and shown in the drawings herein described for forming an ornamental grate-frame, summer-piece and fender, substantially as described.

Witnesses.
